COLLAPSIBLE STRETCHER

John Stephen Dunn, Syracuse, N. Y.

Application January 27, 1939, Serial No. 253,217

4 Claims. (Cl. 5—82)

This invention relates to stretchers and more particularly to a stretcher of the collapsible type.

An object of this invention is to provide a stretcher and means in the form of straps for use with the stretcher so as to hold a person in the stretcher against longitudinal movement relative to the stretcher.

Another object of this invention is to provide a stretcher of this type which is designed particularly for use in removing injured or disabled persons from buildings so that the stretcher may be lowered on the outside of a building with a person secured thereto so as to hold the person on the stretcher with as much comfort as possible.

A further object of this invention is to provide a stretcher of this kind which is adapted to be made substantially and entirely of metal and which is foldable or collapsible so as to occupy a relatively small amount of space and which may be extended to a full length stretcher so that a normal size person may be secured in the stretcher and the stretcher placed in a vertical position for lowering the person and stretcher on the cut-side of a building.

A still further object of this invention is to provide an improved locking means for locking the stretcher sections together in extended position.

30 With the foregoing objects and others which may hereinafter appear, the invention consists of the novel construction, combination and arrangement of parts as will be more specifically referred to and illustrated in the accompanying drawings wherein is shown an embodiment of the invention, but it is to be understood that changes, variations and modifications may be resorted to which fall within the scope of the invention as claimed.

40 In the drawings:

Figure 1 is a detail top plan of a stretcher constructed according to an embodiment of this invention.

Figure 2 is a detail side elevation of the stretcher.

Figure 3 is a bottom plan of the stretcher.

Figure 4 is a detail side elevation of the stretcher in collapsed position.

Figure 5 is a detail end elevation of the foot or end of the stretcher.

Figure 6 is a detail end elevation of the head or upper end of the stretcher.

Figure 7 is a sectional view taken on the line 1—1 of Figure 1.

55 Figure 8 is a fragmentary enlarged longitudi-

nal section partly in detail of the locking means for locking the two stretcher sections in extended or operative position, and

Figure 9 is a sectional view taken on the line 9—9 of Figure 8.

Referring to the drawings, the numerals 10 and 11 designate generally a pair of stretcher sections which are hingedly connected together by means of a hinge 12. The hinge 12 has one leaf 13 thereof secured as by rivets, spot welding or other fastening means 14 to the upper end of the lower stretcher section 10 and the opposite leaf 15 of the hinge 12 is secured to the lower end of the upper stretcher section 11 by rivets, spot welding or other like fastening means 16. The 10 lower stretcher section 10 comprises an elongated bottom plate 17 provided with upturned longitudinal or side edges 18 forming a trough of suitable depth and an arcuate foot plate 19 overlaps the lower end of the bottom plate 17 and 20 is secured thereto as by rivets, welding or the like as indicated at 20. The concave side of the foot plate 19 is disposed on the side of the plate 17 having the side walls or flanges 18 and the convex side of the foot plate 19 is provided with 25 a pair of eyes or rings 21 which provide a means whereby a pair of flexible members in the form of ropes or cables 22 may be secured to the eyes 21 in order to steady the stretcher while the stretcher is in a vertical position and is being 30 lowered on the outside of a building.

A hand rail 23 extends longitudinally of each side wall or flange 18 and is supported in spaced relation thereto by means of a plurality of supporting arms 24 which are secured at their lower 35 ends as at 25 to the side walls 18. The lower or inner ends of the arms 24 are disposed on an obtuse angle to the length of the arms 24 so that the outer looped ends 26 of the arms 24 will be outwardly offset from the side walls 18. The 40 inner ends 25 of the arms 24 may be secured on the inside of the side walls 18 by rivets 27, spot welding or other suitable fastening means. The hand rails 23 are preferably constructed in tubular form and are provided with caps 28 at one 45 end thereof so as to hold the hand rails 23 against movement longitudinally of the bottom member 10. The hand rails 23 may be suitably secured as by welding, rivets or the like to the looped portions 26 of the supporting arms 24. 50

A leg strap 29 extends about the two hand rails 23 being looped about the hand rails 23 and the strap 29 is provided with a relatively wide elongated pad member 30 which is adapted to engage the legs of the person positioned in the stretcher 55

so as to hold the legs against bending and preferably, the strap 29 with the pad 30 extends substantially across the knees of the person in the stretcher. In the present instance, there are 5 three of the supporting arms 24 on each side of the bottom section 10 and the strap 29 engages between the lowermost pair of supporting arms 24 and may be moved longitudinally of the hand rails 23 to the limit permitted by the lowermost 10 pair of supporting arms 24. The upper end of each hand rail 23 is provided with a hook portion 31 and a slidable and tubular locking member 32 is slidable on each hand rail 23 adjacent the upper end thereof.

15 The upper stretcher member or section 11 is provided with a bottom plate 33 having upwardly bent side walls or flanges 34 similar to the flanges 18. The lower end of the upper section 11 is adapted to abut against the upper end of the 20 lower section 10 when these two sections are in extended position and the lower ends of the side walls or flanges 34 are adapted to abut against the upper ends of the side walls or flanges 18 so as to provide a substantially continuous channel from end to end of the stretcher. As shown 25 in the drawings, the side walls of the lower section 10 taper or converge in a downward direction and the side walls 34 of the upper section 11 also converge in a downward direction being formed 30 as a continuation of the flanges or side walls 18. A hand rail 35 is disposed at each side of the upper section 11 and is supported in outwardly offset relation to the side walls 34 by means of a plurality of longitudinally spaced apart supporting arms 35 35. The supporting arms 36 have eyes or sleeves 37 at their upper or outer ends which tightly engage about the tubular hand rails 35. Each hand rail 35 is provided with a cap 38 at the upper end thereof so as to hold the rail 35 against 40 downward movement. If desired, the rails 35 may be spot welded or otherwise tightly and securely held in the sleeves 37. The lower ends of each side rail 35 is provided with a hook portion 39 which is complementary to the hook portion 31 and the two hook portions 31 and 39 45 adapted to interlock as shown in Figure 8 and then the sleeve 32 is adapted to be disposed about the interlocked portions of the rails 23 and 35 so as to securely hold the hand rails 35 against 50 release from each other. If desired the sleeve 32 may be provided with a suitable holding means in the form of a spring pressed pawl or locking means so as to hold the sleeve 32 in operative or locked position.

55 The upper end of the upper section 11 is provided with a head member in the form of a plate 40 which is secured as by rivets 41, welding or the like to the bottom plate 33. The plate 40 extends upwardly from the plate 33 and is provided 60 with a right angular upper end portion 42. A V-shaped extension 43 is formed integral with the flange or extension 42 and is disposed substantially parallel with the plate 40 as shown in Figure 2. The V-shaped extension 43 is provided 65 with an eye 44 adjacent the upper or convergent end thereof in which a hook 45 carried by a flexible member 46 is adapted to engage. The flexible member 46 may be a rope which is used for lowering the stretcher when a person is strapped thereon. A pair of reinforcing rings 47 are disposed 70 on opposite sides of the extension 43 so as to reinforce the extension about the opening 44.

In order to firmly hold a person in the upper stretcher section 11, I have provided a pair of body straps 48 and 49 which are slidable on the 75

hand rails or bars 35 and extend across the bottom 5 33. The strap 48 is provided with an elongated pad 50 and the strap 49 is provided with a similar pad 51. These two straps 48 and 49 with the pads 50 and 51 are adapted to engage the torso or body of the person positioned in the upper stretcher section 11.

A pair of crotch or leg straps 52 and 53 are secured to rings 54 and 55 respectively which are carried by strap members 56 and 57 engaging the 10 opposite side rails 35. These crotch straps 52 and 53 are of looped configuration and are adapted to engage about the thighs of the person positioned in the stretcher so as to firmly hold the person against longitudinal or downward movement in the stretcher comprising the two sections 10 and 11. 15

In the use of this stretcher, the stretcher when in collapsed position will be disposed as shown in Figure 4 with the under sides of the sections 10 and 11 in confronting relation. The stretcher in collapsed position will occupy a relatively small amount of space and may be carried in a relatively small compartment or space. When it is desired to open the stretcher to receive a person, 25 the two sections 10 and 11 are swung on the hinge 12 so that the locking portions 31 and 39 will interengage and then the locking or holding sleeves 32 are moved over the locking portions 31 and 39 so that these locking portions will be firmly 30 held against disengagement. The person to be carried by the stretcher is positioned flat on the stretcher and the straps 29, 48 and 49 are then tightened across the legs and body respectively 35 of the person. The crotch straps 52 and 53 are engaged with the legs of the person so that when the stretcher is raised to a vertical position being in a hanging position from the cable or rope 46, the weight of the person will be substantially 40 entirely borne by the crotch straps 52 and 53. 40 The feet of the person are adapted to rest on the foot member 19 so as to relieve the straps 52 and 53 of undue strain and also to prevent undue 45 discomfort to the patient by the straps 52 and 53. In certain instances the straps 52 and 53 may be 45 dispensed with and transverse or cross straps substituted therefor.

This stretcher may be made out of relatively light weight metal having the necessary tensile strength being preferably constructed out of 50 aluminum or an alloy so that the stretcher will not in itself be unduly heavy but will have the necessary inherent strength to keep the stretcher from bending. When the stretcher is being lowered by means of the flexible members 46 the 55 lower end of the stretcher may be guided by means of the flexible members 22 which are secured to the eyes 21 carried by the foot member 19. A stretcher constructed according to this invention may be manufactured at a relatively 60 small cost, will last indefinitely due to the fact that it is constructed of metal, and is sufficiently braced against longitudinal bending so that it will properly support a person. This stretcher has been designed particularly for use in removing 65 persons from buildings having no elevators or buildings which have caught on fire or for other similar emergencies where a non-collapsible stretcher cannot be used in order to remove a person from a building.

70 What I claim is:

1. A collapsible stretcher comprising a pair of channel shaped sections, means hingedly securing said sections together, a pair of hand rails for each section and disposed in parallel relation 75

to the sides thereof, supporting arms secured to said sections and said rails for supporting a rail of one section in alignment with an adjacent rail of the other section when the sections are in 5 extended position, interengaging locking means carried by said rails, a pair of locking sleeves slidably carried by certain of said rails and engageable about said locking means to hold said locking means in locked position, and a foot 10 supporting member carried by an end of one of said sections and projecting in the direction of the open side of the channel thereof.

2. A collapsible stretcher comprising a pair of channel shaped sections, means hingedly securing 15 said sections together, a pair of hand rails for each section and disposed in parallel relation to the sides thereof, supporting arms secured to said sections and said rails for supporting a rail of one section in alignment with an adjacent rail 20 of the other section when the sections are in extended position, interengaging locking means carried by said rails, a pair of locking sleeves slidably carried by certain of said rails and engageable about said locking means to hold said locking 25 means in locked position, a foot supporting member carried by an end of one of said sections and projecting in the direction of the open side of the channel thereof, a plate secured to the opposite end of the other member, a right angle exten- 30 sion carried by said plate and disposed transversely of said other section, and a V-shaped member carried by said extension and extending outwardly thereof and in parallel relation to said plate, said V-shaped member having an opening 35 through the convergent end thereof to receive an end of a supporting means.

3. A collapsible stretcher comprising a pair of complementary sections, and means hingedly se-

curing said sections together, each of said sections comprising an elongated relatively rigid bottom member, upstanding side walls carried by said bottom member, upwardly and outwardly extending rail supporting arms carried by said side walls, a sleeve carried by each arm, a pair of hand rails engaging in the sleeves of said arms, a rail of one section being disposed in axial alignment with a rail of the other section when the sections are in extended position, and interlocking means carried by the inner ends of said rails for holding said sections in extended position.

4. A collapsible stretcher comprising a pair of complementary sections and means hingedly securing 15 said sections together, each of said sections comprising an elongated relatively flat bottom wall, upstanding side walls integral with the opposite edges of said bottom wall, a plurality of upwardly and outwardly inclined arms 20 secured to said side walls, a sleeve integral with the upper end of each arm, an elongated hand rail at each side of a section engaging in said sleeves, the rails of one section being disposed in axial alignment with the rails of the other section 25 when the sections are in extended position, interengaging locking means carried by the inner ends of said rails, a pair of locking sleeves slidably engaging said rails and engageable over said locking means to hold said locking means against 30 separation, an inwardly projecting foot plate carried by the outer end of one of said sections, an inwardly projecting head member carried by the outer end of the other section, and an extension carried by said head member provided 35 with means to receive a flexible supporting means.

JOHN S. DUNN.
